UNITED STATES PATENT OFFICE.

MAURICE F. FITZGERALD, OF WINSTED, CONNECTICUT, ASSIGNOR TO THE FITZGERALD MANUFACTURING COMPANY, OF TORRINGTON, CONNECTICUT, A CORPORATION OF CONNECTICUT.

ELECTRIC TOASTER.

1,426,284.

Specification of Letters Patent. Patented Aug. 15, 1922.

Application filed January 13, 1921. Serial No. 436,928.

To all whom it may concern:

Be it known that I, MAURICE F. FITZGERALD, a citizen of the United States, residing at Winsted, in the county of Litchfield, State of Connecticut, have invented certain new and useful Improvements in Electric Toasters, of which the following is a description, reference being had to the accompanying drawing and to the figures of reference marked thereon.

This invention relates to electric toasters for bread, and more particularly to the mechanism for presenting both sides of a slice of bread to the source of radiant heat.

One of the objects of this invention is to provide a device of the above character in which there is provided a member hinged to the support so as to swing away from the source of radiant heat, together with a slice holder pivotally mounted on said hinged member and adapted to be rotated about its pivot when the swinging member is swung outwardly so that either side of the slice may be presented to the source of radiant heat.

Another object of this invention is to provide a device of the above character in which the slice holder is pivotally mounted on a member having in turn a hinged connection to one of the end plates between which the usual source of radiant heat is located, together with an operating member connected to both the swinging member and to the slice holder, whereby when this operating member is moved in the arc of a circle to swing the member outwardly, it may also be given a slight rotary motion to thereby rotate the slice holder on its pivot so that the opposite side of the slice may be presented to the source of radiant heat.

A further object of this invention is to provide a toast holder of the above character which is of sturdy construction, of few parts, and simple in operation.

These and other objects will in part be obvious and will in part be hereinafter more fully disclosed.

Referring more particularly to the accompanying drawings:—

Figure 1 represents a side elevation of the toaster;

Fig. 2 is a plan view thereof with the top plate broken away;

Fig. 3 is an end sectional view; and
Fig. 4 is a sectional view on the line 4—4 of Fig. 1.

In general, the device comprises the usual open-faced standard, provided with supporting means for the source of radiant heat for providing opposed heating surfaces. To this support, in any desired manner, is hingedly mounted a bracket member adapted to swing in the arc of a circle away from said source of heat and pivotally mounted on the outer portion of this swinging bracket is a slice holder of any desired type. The pivotal connection between the swinging arm and slice holder is provided with an operating knob or handle so that when the same is grasped and swung outwardly, the swinging member will move in the arc of a circle to open position, at which time by a slight rotation of the operating handle, the slice holder can be rotated on its pivot so that either side of the slice may be presented to the source of heat when the member is swung back into position.

Referring more particularly to the accompanying drawing, the device embraces the usual base 1 adapted to support, in spaced relation, the usual end plates 7 and 8. In the present instance, these end plates are secured to the base by forming each end plate with spaced ears 2 and 3 adapted to enter corresponding slots 4 and 5 in the base. The inner faces of these spaced ears or projections 2 and 3 are notched to receive a locking member 6, preferably in the form of a metal strip. Between these two end plates 7 and 8, there is fastened the lower support for the source of radiant heat, which, in the present instance, is the usual electric heating coil. This support comprises an inverted cradle-shaped member 9 provided with ears 10, through which screws 11 pass into the end plates whereby the support is held in fixed position. This lower support is provided with any desirable means for sustaining the heating coil in fixed position and is also provided with the usual electrical contacts 12 and 13. Between the upper portion of these end plates is arranged the upper support 14 for the heating coil which is preferably identical in construction with the lower one, but reversed in position as clearly shown in Fig. 3, and the spaced ears 15 of this support are pro-

vided with holes 16 for a purpose herein-after set forth. The usual flat top plate 17 for the toaster is slotted as at 18 and 19 to provide a downwardly bent tongue 20, 5 likewise perforated. In assembled relation the upper support is located between the two side plates and the flat top rests upon the upper support, and the fastening screws 21 pass through registering perforations in 10 the downwardly bent tongues of the upper support, whereby these three members are held in assembled position by these fastening screws.

Spacing plates 22 and 23 are located at 15 each end plate between the upper and lower supports for the heating coil. These spacing plates are cut away as at 24 and 25 to exactly conform to the curvature of the upper and lower supports, each one of these 20 spacing plates, however, being held in assembled position by ears 26 passing through slots 27 in the lower heating coil support 9. These spacing plates are provided with parallel rows of spaced perforations 28 and 25 29 into which are lodged the rods 30 which form a guard for the electric heating coil and also prevent the slice holder from swinging into contact with the heating coil and injuring the same.

In order to present the slice of bread or other object to the electric heating coil or other source of radiant heat, so that either or any side of the slice may be presented thereto at the will of the operator, the brackets or swinging members 31 are hinged or pivotally mounted to the support so as to swing outwardly or away from the source of heat. While these swinging arms may be hinged directly to the base on the horizontally arranged hinged connection, in the present instance, it is preferred to pivot them by means of the spaced hinges 32 and 33 to the end plate, as shown. Fastened to each side of the end plate between the hinges 45 is a plate 34 having an outwardly bent portion 35 adapted to limit the outward swinging movement of the swinging member 31. As will be noted, in the present instance, the opposed slice holders are mounted identically on each side of the same end plate, by which construction a single spring 36 attached to the swinging arms 31 will suffice to keep these swinging arms in innermost position spaced from the source of radiant 55 heat.

It will, of course, be obvious that one swinging arm 31 may be mounted on one end plate, and the other swinging arm mounted on the other end plate, in which instance, 60 two springs would have to be used.

The open-ended slice holders 37 may be of any desired shape and construction, and are provided with upper and lower pivotal pins 38 and 39, respectively, preferably formed 65 intermediate the ends of the slice holders,

which pivotally engage corresponding perforations formed in the outer extremity of the swinging members 31. The upper portion of the upper pivotal pins 39 are threaded to receive wooden or other known heat 70 conducting operating knobs or handles 40 and 41.

By means of this construction, when it is desired to toast the other side of a slice of bread, by pulling the operating handle 40 outwardly, the swinging member 31 is swung outwardly in the arc of a circle away from the source of radiant heat, and when in its outer position, by means of a slight rotation of this operating handle, the slice holder 80 may be rotated about its pivotal pin 38 whereby any side of the slice may be again presented to the source of radiant heat when the swinging arm is permitted to be swung back into toasting position by means of the 85 spring 36.

It will also be noted that when the slice holder is in its outermost position, due to the pivotal construction, the slice holder may be rotated so that the operator may not only 90 toast the opposite side, but may retoast the same side if it has not been sufficiently toasted.

It will be apparent from the above that the present device embraces a most economically constructed toaster wherein a single operating member provides means at the will of the operator for effecting the desired 95 toasting of the slice of bread.

It will be obvious that minor changes in 100 the details of construction and the arrangement of the parts may be made without departing from the spirit of the invention, as set forth in the appended claims.

Having thus described the invention, what 105 I claim as new and desire to secure by Letters-Patent, is—

1. In a toaster, a support including spaced end plates, means for supporting therebetween a source of radiant heat, a substantially U-shaped bracket vertically pivoted to one of said end plates and adapted to swing outwardly away from said source of heat, a slice holder mounted on a vertical axis on the free ends of said bracket, a turning knob 110 on said pivot whereby said bracket may be swung outwardly and the slice holder rotated about its pivot to present either side thereof to the source of heat.

2. In a toaster, a support including spaced 115 end plates, means for supporting therebetween a source of radiant heat, a substantially U-shaped bracket vertically pivoted to one of said end plates and adapted to swing outwardly away from said source of heat, a slice holder pivotally mounted in the free 120 end of said bracket, a hand knob secured to the upper pivot of said slice holder whereby said bracket may be swung outwardly and said slice holder rotated about its pivot to 125 130

present either side of the slice holder to the source of heat.

3. In a toaster, a support including spaced end plates and upper and lower supports for 5 a source of radiant heat, a substantially U-shaped bracket arranged with its arms extending horizontally and hinged on vertical pivots at its intermediate portion to an end plate so as to swing outwardly from said 10 source of heat, means tending to maintain said bracket in inwardly spaced position relatively to said source of heat, a slice
- holder having upper and lower studs pivotally mounted on the upper and lower arms respectively, of said bracket, and a turning 15 knob rigid with the upper portion of the upper stud projecting through the upper arm of said bracket whereby said slice holder may be swung outwardly and rotated about its pivots to present either side of said slice 20 holder to said source of heat.

In testimony whereof, I affix my signature.

MAURICE F. FITZGERALD.
